UNITED STATES PATENT OFFICE.

CHARLES S. OLSON, OF DULUTH, MINNESOTA, ASSIGNOR OF ONE-HALF TO M. C. ALBENBERG, OF DULUTH, MINNESOTA.

CONDIMENT-SHAKER.

968,257.

Specification of Letters Patent. Patented Aug. 23, 1910.

Application filed May 9, 1910. Serial No. 560,159.

To all whom it may concern:

Be it known that I, CHARLES S. OLSON, a citizen of the United States, residing at Duluth, in the county of St. Louis and State of Minnesota; have invented certain new and useful Improvements in Condiment-Shakers; and I do hereby declare the following to be a full, clear, and exact description of the invention, such as will enable others skilled in the art to which it appertains to make and use the same.

My invention relates to condiment shakers adapted to contain different condiments in separated compartments from which either may be shaken without the other, and has for its object the provision of an improved shaker of such type.

It consists of the constructions, combinations and arrangements of parts hereinafter described and claimed.

In the drawings, Figure 1, is a perspective view of one form of my invention. Fig. 2, is a bottom plan view of a cover forming part of said invention. Fig. 3, is a vertical section of a fragment of a reservoir and of said cover, on the line A—B of Fig. 2. Fig. 4, is a vertical section on the line C—D of Fig. 3. Fig. 5 is a perspective view of said reservoir, with the cover omitted. Fig. 6, is a perspective view of a modified form of said invention. Fig. 7, is a fragmentary vertical section of said modified form, on the line E—F of Fig. 6. Fig. 8 is a fragmentary vertical section approximately on the line G—H of Fig. 6.

In the drawings, 1 is a reservoir containing a plurality of compartments, as 1^a and 1^b, separated from each other by a partition 2 extending upward to a cover 3 by means of which cover said compartments may be closed at the top. Said cover preferably has formed thereon a transversely extending rib 3^a, longitudinally grooved or indented in its lower face to receive one of the edges of said partition. Said cover has a plurality of perforations as 4 formed in its upper face on one side of said rib and has a plurality of perforations 4^a formed therein on the opposite side of said rib, and is provided with a suitable flange 4^b for securing it to the reservoir 1. Said flange may be formed integral with the top of the cover as in Figs. 6, 7 and 8, or may be constructed as a separate fastening ring, as in Figs. 1, 3 and 4. The edge of the partition 2 is pref-

erably pressed into the offset space 3^a of the cover both when the flange 4^b is integral with the cover and when said flange 4^b is constructed as a separate ring. Pivottally secured in any suitable manner or by any suitable means, as at 3^a and 6^a to the lower face of the top of said cover are two closure plates, 5 and 6 with which are engaged the opposite ends, respectively, of a U-shaped actuating bar 7 for swinging said wings on their pivots. Said actuating bar intermediate of its ends extends outwardly through the side of said cover and between it and the outer face of said cover is interposed a spring 8 of any suitable construction for retracting said bar, whereby said closure plates are held in retracted normal position. Said bar is adapted to be manually operated against the action of said spring. Said closure plates are perforated as at 5^b and 6^b respectively, the perforations in one of said closure plates registering, when it is in retracted position, with the perforations 4^a in the overlying position of the cover, the perforations in said closure plate being closed by the cover when the closure plate is in actuated position, and the perforations in the other closure plate registering, when it is in actuated position, with the perforations 4 in the overlying position of said cover, and being closed by said cover when said closure plate is in retracted position.

In the modified form shown in Figs. 6, 7 and 8, the partition 2 which in operative position divides the reservoir into compartments, is in the form of an inverted frustum flattened on one side near the center line of the cover so that the straight edge of the partition may enter the groove in the lower face of the rib on the cover. The closure plate 6 is inclosed by the upper edge of the partition in said modified form, said partition in said form meeting the cover all around said closure plate 6, space being provided between said closure plate and partition to allow the closure plate to swing on its pivot and a passage being provided through the partition for one arm of said U-shaped bar. In said modified form a removable bottom of any suitable construction is provided for said chamber 1^a as a cork 8. In said modified form said partition is preferably secured to the cover and projected into the reservoir so that danger of intermixing of the contents of either

chamber over the partition and beneath the cover is entirely obviated. Said construction may be modified in minor particulars within the scope of the appended claim.

5 I claim—

In a condiment shaker, the combination of a reservoir divided into two compartments by a partition independent of the walls of said reservoir and inclosing one of 10 the compartments, a perforated cover for said reservoir, two perforated closure plates pivoted to the lower face of said cover by independent pivots, and adapted to swing in a plane parallel with the lower face of 15 said cover, actuating means for swinging said closure plates on their pivots, means for retracting said actuating means, one of said closure plates being surrounded by the upper end of said partition, said partition 20 having a port formed therein below its upper end for charging the chamber inclosed

by said partition, a movable closure for said port, the perforations in one of said closure plates being adapted when the closure plate is in actuated position to register with some 25 of the perforations in said cover and when the closure plate is in retracted position to be closed by said cover, the perforations in the other of said closure plates being adapted when the closure plate is in actuated position to be closed by said cover and when the closure plate is in retracted position to register with others of the perforations in 30 said cover, said partition being secured to said cover.

In testimony whereof I hereunto affix my signature, in presence of two witnesses.

CHARLES S. OLSON.
